US00D760054S

(12) **United States Design Patent**
Huttunen

(10) **Patent No.:** **US D760,054 S**
(45) **Date of Patent:** **** Jun. 28, 2016**

(54) **AXE**

(71) Applicant: **Fiskars Garden Oy Ab**, Billnäs (FI)

DE 30 06 968 A1 9/1981
DE 298 13 762 U1 8/1999

(72) Inventor: **Aaro Huttunen**, Billnäs (FI)

(Continued)

(73) Assignee: **Fiskars Garden Oy Ab**, Billnäs (FI)

OTHER PUBLICATIONS

(**) Term: **14 Years**

U.S. Appl. No. 29/388,574, filed Mar. 20, 2011, Block et al.
(Continued)

(21) Appl. No.: **29/521,102**

Primary Examiner — Phillip S Hyder
(74) *Attorney, Agent, or Firm* — Foley & Lardner LLP

(22) Filed: **Mar. 19, 2015**

(30) **Foreign Application Priority Data**

Sep. 22, 2014 (EM) 002542365-0004
Sep. 22, 2014 (EM) 002542365-0005

(51) **LOC (10) Cl.** **08-02**

(57) **CLAIM**
I claim the ornamental design for an axe, as shown and described.

(52) **U.S. Cl.**

USPC **D8/76**

(58) **Field of Classification Search**

USPC D8/75, 76, 77, 78, 79; D22/118
CPC B25D 1/00; B25D 1/04; B26B 23/00;
B25G 1/00; B25G 3/10
